UNITED STATES PATENT OFFICE.

FITCH H. BEACH AND FRED S. BEACH, OF CHARLOTTE, MICHIGAN.

WHEEL SCRAPER.

Application filed December 13, 1922. Serial No. 606,724.

To all whom it may concern:

Be it known that we, FITCH H. BEACH and FRED S. BEACH, citizens of the United States, residing at Charlotte, in the county of Eaton 5 and State of Michigan, have invented a new and useful Wheel Scraper, of which the following is a specification.

The device forming the subject matter of this application is a scraper, and one object 10 of the invention is to provide a novel spring means for raising the frame of the scraper and the scoop after the scoop has been loaded, considerable work being taken off the operator.

Another object of the invention is to provide novel means for limiting the forward 15 swinging movement of the Johnson bar. Another object of the invention is to provide novel means for holding the Johnson bar 20 against movement when the scoop is elevated.

A further object of the invention is to supply novel means whereby the rear end of the scoop will be prevented from tilting either upwardly or downwardly. A further 25 object of the invention is to improve the device that several of them may be yoked together tandem, to be drawn by a tractor or otherwise.

It is within the province of the disclosure 30 to improve generally and to enhance the utility of devices of that type to which the invention appertains.

With the above and other objects in view, which will appear as the description proceeds, the invention resides in the combination and arrangement of parts and in the details of construction hereinafter described 35 and claimed, it being understood that, within the scope of what is claimed, changes in the 40 precise embodiment of the invention shown can be made without departing from the spirit of the invention.

In the accompanying drawings:

Figure 1 shows in top plan, a device constructed in accordance with the invention; 45 Figure 2 is a side elevation wherein one ground wheel has been removed; Figure 3 is a cross section on the line 3—3 of Figure 1; Figure 4 is a section on the line 4—4 of 50 Figure 1, parts being omitted.

In the drawings the device is shown as comprising a main frame 1 including side bars 2 between which is disposed a loop-shaped brace 3. The side bars 2 have rearwardly converging portions 4 terminating in 55 parallel parts 5 between which is held a beam

6 carrying a vertical loop 7 adapted to cooperate with a horizontal loop 8 on a like machine, a universal joint being afforded by the parts 7 and 8 so that one machine may 60 be yoked to another, thereby enabling several machines to be drawn along tandem. A rear platform 9 is mounted on the portions 4 of the side bars 2 and on the beam 6. The side bars 2 have forwardly converging portions 65 7 merging into parallel parts 11 between which is secured a beam 12 having any suitable draft means 14 whereby the machine may be assembled with a tractor or the like. A forward platform 15 is mounted on the 70 parts 10 of the side bars 2 and upon the beam 12. The forward converging ends 16 of the brace member 3 are connected to the beam 12. A cross bar 17 is superposed on the side bars 2 and is secured thereto. The bar 17 75 carries a loop-shaped stop 18 and a latch 19.

The numeral 20 marks an arched axle having spindles 21 whereon ground wheels 22 are journaled, portions of the spindles being squared as shown at 23. Crank arms 24 are held on the squared portions 23 of the axle spindles 21. Radius arms 25 are pivoted at 26 to the cranks 24 and are provided at their upper ends with arcuate grooved treads 27 across which extends a flexible element 28, preferably in the form of a chain, the rear ends of the chains being secured as shown at 29 to the side bars 2 of the frame 1 at points to the rear of the axle 20. The forward ends of the chains 28 are attached to the rear 90 ends of retractile springs 30, the forward ends of the springs being secured at 31 to the cross bars 17.

The numeral 32 marks a support and operating member, technically known as a 95 Johnson bar. The element 32 comprises a main member 33, the forward end of which is secured as shown at 34 to the intermediate part of the arched portion of the axle 20.

The part 32 comprises L-shaped auxiliary 100 members 35, secured to the member 33 and secured as indicated at 36 to the depending parts of the arch of the axle 20. Side hangers 37 are provided. The upper ends of the side hangers 37 are pivoted at 38 to 105 the forward ends of the parts 25 of the member 32. Intermediate their ends, the side hangers 37 are pivoted as at 39 to the side bars 2 of the frame 1. The lower ends of the hangers 37 are pivoted at 40 110 to the sides of the scoop 41. Depending links 42 are pivoted upon the forward ex-

tremities of the parts 35 and are pivoted at their lower ends to latches 43 which, in turn, are pivotally supported as at 44 on the side bars 2 of the main frame 1. The latches 43 are adapted to cooperate with keepers 45 on the sides of the scoop 41. A loop-shaped retainer 46 is mounted on the rear wall of the scoop 41, the retainer extending beneath one of the members 35 of the Johnson bar 32, as shown in Figure 1 and extending above the member 3 which forms part of the main frame 1. The scoop 41 is equipped with a rearwardly projecting handle 47. A locking lever 48 is fulcrumed intermediate its ends on the rearwardly projecting portion of the Johnson bar 32, as shown at 49. The lower end of the locking lever 48 is adapted to engage with a keeper 50 on the rear wall of the scoop 41. A retractile spring 51 extends between the lever 48 and the platform 9 and holds the lever engaged with the keeper 50. A latch 52 is mounted to swing on a bracket 53 carried by the rear platform 9 and is adapted to engage with the rearwardly projecting part 33 of the member 32.

In practical operation, a person standing on the platform 9 may detach the latch 52 from the member 33 of the Johnson bar, the Johnson bar being swung upwardly and forwardly, the loop-shaped axle 20 being rocked, the scoop 1 being lowered into filling position, and the latch 43 being engaged with the keeper 45. As the scoop 41 fills, the axle 20 is rocked, and the cranks 24 impart movement to the radius arms 25, the springs 30 being extended. The result is that when it is desired to restore the parts to the position shown in Figure 2, this can be done with a small expenditure of effort on the part of the operator, the scoop 41 and the frame 1 being raised partly through the action of the springs 30 with a little additional effort on the part of the operator. The retainer 46 extends above the part 3 of the main frame 1, as shown in Figure 1, and, consequently, the rear end of the scoop 41 is prevented from swinging downwardly. Further, because the retainer 46 extends beneath one of the parts 35 of the Johnson bar 32, the scoop 41 will be prevented from swinging upwardly when the member 33 of the John-

son bar is engaged with the latch 53. When the scoop 41 is disposed in dumping position, the stop 18 coating with the member 32 prevents the said member from swinging forwardly to an extent sufficient to injure a person standing on the platform 15.

What is claimed is:—

1. In a device of the class described, an arched axle; wheels carried thereby; a frame extended forwardly and rearwardly of the axle; a crank on the axle; a radius arm pivoted to the crank; a flexible member connected to the frame in front of the axle and to the rear thereof, the flexible member extending across the radius arm and including a retractile spring; an operating member connected to the arched portion of the axle; a scoop; and means for suspending the scoop and the frame from the operating member. 60

2. A device of the class described, constructed as described in claim 1 and further characterized by the provision of latch means on the rear portion of the frame and engaging the operating member to hold the 75 scoop elevated.

3. A device of the class described, constructed as set forth in claim 1 and further characterized by the provision of latch mechanism on the rear portion of the frame 80 and engaging the operating member to hold the scoop elevated, the frame being provided on its forward portion with a stop which limits the forward swinging movement of the operating member when the scoop moves 85 to dumping position.

4. A device of the class described, constructed as set forth in claim 1 and further characterized by the provision of latch mechanism on the rear portion of the frame and engaging the operating member to hold the scoop elevated, the scoop being provided with a retainer engaged above the frame and beneath the operating member, to hold the rear end of the scoop against vertical swinging movement. 90

In testimony that we claim the foregoing as our own, we have hereto affixed our signatures.

FITCH H. BEACH.
FRED S. BEACH.
